UNITED STATES PATENT OFFICE.

FREDERICK C. HOFFMAN, OF HARTFORD, CONNECTICUT, ASSIGNEE TO HOFFMAN & HAYNES COMPANY, OF HARTFORD, CONNECTICUT.

MOP HEAD.

Application filed September 11, 1922. Serial No. 587,269.

To all whom it may concern:

Be it known that FREDERICK C. HOFFMAN, citizen of the United States, residing at Hartford, in the county of Hartford and 5 State of Connecticut, has invented certain new and useful Improvements in Mop Heads, of which the following is a specification.

This invention relates to mop heads, and 10 among the objects of the invention are the provision of an article of this character which is simple in construction, effective in action and by which the mop can be connected with the head without the necessity 15 of the user touching the mop.

In the drawing accompanying and forming part of the present specification, I have shown in detail a form of embodiment of the invention which to enable those skilled 20 in the art to practice the same will be set forth fully in the following description. Obviously, I am not restricted to this exact disclosure. I may depart therefrom in a number 25 of respects within the scope of the invention defined by the claim following said description.

Referring to said drawing:

Fig. 1 is a top plan view of a mop involving the invention.

Fig. 2 is a side elevation of the same.

Fig. 3 is a cross section on the line 3—3 of Fig. 2 looking toward the left.

Like characters refer to like parts throughout the several views.

The invention resides primarily in the head of the mop. The head shown is denoted in a general way by 2, and it is carried by a handle or rod such as 3, which usually consists of an elongated piece or staff of wood ordinarily of cylindrical form. Near the forward end of the handle there may be fitted thereto as by driving, the sleeve or band 4 and which functions as I will hereinafter explain.

The head comprises as shown two skeleton jaws as 5 and 6 which usually consist of heavy wire. The lower jaw 5 is practically in the form of a loop, the inner bar of which or that in adjacency to the handle 3 is split or divided. From the split or divided portion of the inner bar extend the pivots 7

which are seated in eyes 8. These eyes 8 are carried upon the outer jaw 6.

As shown, the upper jaw 6 is in the form of a loop, the inner bar of which is split and 55 at the ends of the inner bar the eyes or loops 8 are situated. From the upper whorles of the eyes 8 are extended rearwardly arms 9 which fit closely longitudinal grooves or channels 10 in the forward end of the handle 3 and are extended under the band or sleeve 4.

The arms 9 at their back ends have lateral branches 11 terminating in hooks 12 which constitute keepers for latching members 65 hereinafter described.

From the pivots 7 there extend rearwardly the arms or latch members 13 which are shown in full lines in Figs. 1 and 2, as occupying their normal or operative positions 70 at which point they are under the hooks 12, the jaws 5 and 6 at this time being held closed and clamping the mop portion 14. To release the mop portion 14 the arms or latch members 13 will be caused to relatively approach each other as by a grip upon them, so that they can be swung from under the hooks or catches 12 and permit the arms 13 to be swung upwardly or outwardly as shown by dotted lines in Fig. 2 thus carrying the jaw 80 5 away from the companion jaw 6 and open the jaws relatively, and release or free the mop portion 14 to insert a new mop portion. This, in fact, can be accomplished without the hands coming in contact with either mop 85 portion.

When a fresh mop portion is to be put in place, it is inserted between jaws 5 and 6 when they are in the open relation as shown in Fig. 2 and when it has been put into place, 90 the jaw 5 will be closed against the jaw 6 by swinging down the arms or latch members 13 and causing them to engage under the hooks 12.

It will be clear that the jaws 5 and 6 are 95 of skeleton formation and although the cloth or mop portion 14 can be inserted through either jaw, both of them being of loop form, the cloth or mop portion is desirably clipped or clamped between the jaws so that the cloth 100 or mop portion extends out from the ends or lateral portions of the jaws and prevents the

metal parts from coming in contact with the wash boards of a room.

What I claim is:

A mop head comprising two loop-like skeleton jaws, one of which has eyes, and the other of which has pivots extending through the eyes, the eyes having arms terminating in hooks, the complementary jaw having resilient latch portions extending from said pivots and which are adapted to

be sprung under said hooks, combined with a rod, and a band fitted around the rod and also over said arms.

In testimony whereof I hereby affix my signature.

FREDERICK C. HOFFMAN.
